HEADBOARD FOR SAILS

Isaac F. Manchester, Jr., New Bedford, Mass.

Application June 2, 1948, Serial No. 30,681

10 Claims. (Cl. 114—115)

1

My invention relates to sails for vessels and in particular to attachments secured to those parts, corners or angles of sails known as heads, throats, peaks, clews and tacks. Although the following description is confined to a triangular fore-and-aft mainsail, the luff-rope of which, when the sail is hoisted or lowered, travels in a groove in a mast, and to attachments secured to the head of the sail; nevertheless this invention is equally applicable to all types of sails, bent to all types of spars with or without grooves, to other bolt-ropes such as head-ropes and foot-ropes as well as luff-ropes and to attachments secured to throats, peaks, clews and tacks as well as heads of sails.

At the present time, the head-board of a triangular fore-and-aft mainsail, the luff-rope of which, when the sail is hoisted and lowered, travels up and down in a longitudinal, vertical groove in the after side of a mast, is fastened to the canvas at the head of the mainsail, but is not attached to the luff-rope. The main halyard is secured to or near the top of the head-board. The results of this arrangement are that the strain of the halyard is on the canvas, wrinkles, bags and/or "hard" spots are produced along the luff and/or in the belly of the sail, the leach is caused to pucker, and the head-board is insecure in relation to the mast.

The principal object of this invention is to eliminate wrinkles, bags, "hard" spots, pockers and the like and to give the sail a good "set," by taking the strain of the halyard off the canvas and applying it to the luff-rope, and by providing a head-board firmly secured in relation to the mast, but free to swing to port or to starboard to conform with the trim of the sail on either tack and capable of being easily hoisted and lowered with the sail.

One feature of this invention is a head-board, not only attached to the canvas of a sail, but also to the luff-rope thereof. Another feature is a head-board having a portion adapted to travel within a groove of a mast, when the sail is hoisted or lowered. A further feature is a hinge between said portion and that part of the head-board to which the canvas is attached.

Other objects and features will appear from the following description taken in conjunction with the accompanying drawings in which:

Fig. 1 is a vertical, fore-and-aft section through a grooved mast showing the head of a sail and the head-board hoisted adjacent to the truck of the mast.

Fig. 2 is a side view of another form of head-board with the sail and mast removed.

Fig. 3 is a cross-sectional view taken along line 3—3 of Fig. 2.

Fig. 4 is a cross-sectional view taken along line 4—4 of Fig. 2, and

2

Fig. 5 is a cross-sectional view taken along line 5—5 of Fig. 1.

The luff of mainsail 1 is secured by such means, as by sewing, around luff-rope or bolt-rope 2, Figs. 1 and 5. On the after side of mast 3 is a longitudinal, vertical groove 4, running substantially the height of the mast, into which the luff of the mainsail and the luff rope are inserted. The canvas of the mainsail leads aft out of the groove through slot 5 between oppositely disposed jaws 6. The latter are so spaced apart as to allow the canvas to pass freely therebetween, but prevent the luff and the luff-rope from escaping aft out of the groove.

15 The head of the mainsail is fastened by such means as by stitches 7, Fig. 1, to head-board 8, which has therethrough small holes 9, Fig. 2, to facilitate sewing the head of the sail to the head-board and larger holes 10 to decrease the weight thereof. Integral with the head-board and on the forward edge thereof is a cylindrical projection 11, Figs. 1, 2 and 3, through the axis of which is a hole 13. Hinged to the projection 11 by means of a pintle 12 is hinge member 14, Figs. 1, 2, 3 and 4, consisting of a cylindrical, tubular piece 15, a neck 16, and two other pieces 17.

The piece 15, located on the forward side of the hinge member 14, has a tubular opening 18 extending throughout the length thereof. The upper end of the luff-rope 2, extending above the top of the luff of the mainsail, is inserted into the opening 18 and is secured therein by lashings 19, or by any other suitable means, such as rivets, through holes 20 in the port and starboard sides of the piece 15 and through the upper end of the luff rope. The piece 15 is of such a size and shape that, together with the upper end of the luff rope and the lashings 19, it may slide freely up or down within the groove 4, when the sail is hoisted or lowered.

40 The neck 16 connects the after side of the piece 15 to the forward sides of the pieces 17 and is sufficiently narrow to pass freely through the slot 5 to allow the sail to be hoisted or lowered. 45 The neck extends through the slot 5 to such a point aft of the jaws 6 that the pieces 17 will not chafe the after side of the mast.

The pieces 17 are located on the upper and lower portions of the after edge of the neck 16. 50 One of them is placed directly above and the other directly below and adjacent to the projection 11. Each has a longitudinal hole 21 placed directly in line with the hole 13 of the projection 11. Pintle 12 is inserted through the holes 13 and 21, and is secured therein preferably by means of lock pin 12a, extending through aligned holes in the lower piece 17 and the pintle.

55 In Fig. 1, the upper piece 17 has a rearwardly extending projection 22 with a hole therethrough to which the halyard 23 is attached preferably

by means of an eye-splice 24, bolt 25 and shackle board 8 is cut away to allow the latter to move 26. The upper, forward corner of the head-freely, to port or to starboard, in relation to the upper piece 17, the bolt 25 and the shackle 26. In Fig. 2, the upper piece 17 has no rearwardly extending projection, the hole to which the halyard is attached is in the upper, forward corner of the head-board, and the pintle 12 extends preferably all the way through the upper piece 17.

Otherwise, except as noted in the preceding paragraph, the head-board illustrated in Fig. 1 is substantially the same as that illustrated in Fig. 2.

The halyard 23 passes in the usual manner aloft and forward over sheave 27, rotatably mounted in a fore-and-aft hole through the truck of the mast, and then leads below to or near the deck.

I claim:

1. A device secured to a corner of a sail and to a spar comprising a board fastened to said sail at said corner and lying in the plane of said sail, a projection on one edge of said board, and a hinge member pivotally secured on one side thereof to said projection and on the other side thereof to a bolt-rope of said sail and to said spar.

2. A device secured fixedly to a corner of a sail and slidably to a spar comprising a board fastened to said sail at said corner and lying in the plane of said sail, a projection on edge of said board, and a hinge member pivotally secured on one side thereof to said projection and on the other side thereof fixedly to a bolt-rope of said sail and slidably to said spar.

3. A device secured fixedly to a corner of a sail and slidably within a groove in a spar comprising a board fastened to said sail at said corner and lying in the plane of said sail, a projection on one edge of said board, and a hinge member pivotally secured on one side thereof to said projection and on the other side thereof fixedly to a bolt-rope of said sail and slidably within said groove.

4. A device secured fixedly to a corner of a sail and slidably within a groove in a spar comprising a board fastened to said sail at said corner and lying in the plane of said sail, a projection on one edge of said board, and a hinge member pivotally secured on one side thereof to said projection and having on the other side thereof a cylindrical tube secured fixedly to a bolt-rope of said sail and slidably within said groove.

5. A device secured fixedly to a corner of a sail and slidably to a spar comprising a board fastened to said sail at said corner and lying in the plane of said sail, a projection on edge of said board, and a hinge member pivotally secured

5 on one side thereof to said projection and on the other side thereof fixedly to a bolt-rope of said sail and slidably to said spar and having on the first mentioned side thereof a perforated extension adjacent to the vertex of said corner.

6. A device secured fixedly to a corner of a sail and slidably to a spar comprising a board fastened to said sail at said corner and lying in the plane of said sail and having a hole therethrough adjacent to the vertex of said corner, a projection on one edge of said board, and a hinge member pivotally secured on one side thereof to said projection and on the other side thereof fixedly to a bolt-rope of said sail and slidably to said spar.

7. A device secured fixedly to a corner of a sail and slidably within a groove in a spar comprising a board fastened to said sail at said corner and lying in the plane of said sail, a projection on one edge of said board, and a hinge member pivotally secured on one side thereof to said projection and on the other side thereof fixedly to a bolt-rope of said sail and slidably within said groove and having on the first mentioned side thereof a perforated extension adjacent to the vertex of said corner.

8. A device secured fixedly to a corner of a sail and slidably within a groove in a spar comprising a board fastened to said sail at said corner and lying in the plane of said sail, a projection on one edge of said board, and a hinge member pivotally secured on one side thereof to said projection and having on the other side thereof a cylindrical tube secured fixedly to a bolt-rope of said sail and slidably within said groove and having on the first mentioned side thereof a perforated extension adjacent to the vertex of said corner.

9. A device secured fixedly to a corner of a sail and slidably within a groove in a spar comprising a board fastened to said sail at said corner and lying in the plane of said sail and having a hole therethrough adjacent to the vertex of said corner, a projection on one edge of said board, and a hinge member pivotally secured on one side thereof to said projection and on the other side thereof fixedly to a bolt-rope of said sail and slidably within said groove.

10. A device secured fixedly to a corner of a sail and slidably within a groove in a spar comprising a board fastened to said sail at said corner and lying in the plane of said sail and having a hole therethrough adjacent to the vertex of said corner, a projection on one edge of said board, and a hinge member pivotally secured on one side thereof to said projection and having on the other side thereof a cylindrical tube secured fixedly to a bolt-rope of said sail and slidably within said groove.

Certificate of Correction

Patent No. 2,488,918

November 22, 1949

ISAAC F. MANCHESTER, JR.

It is hereby certified that errors appear in the printed specification of the above numbered patent requiring correction as follows:

Column 3, line 2, beginning with the word "board", strike out all to and including "head—" in line 3, same column, and insert instead the following: 26. *The upper, forward corner of the head-board 8 is cut away to allow the latter to move;* lines 33 and 61, after "on" insert one;

and that the said Letters Patent should be read with these corrections therein that the same may conform to the record of the case in the Patent Office.

Signed and sealed this 7th day of March, A. D. 1950.
